UNITED STATES PATENT OFFICE.

JOHN L. TAYLOR, OF CHICAGO, ILLINOIS, ASSIGNOR OF ONE-FOURTH TO TAYLOR
PORTABLE STEEL DERRICK COMPANY, A CORPORATION OF ILLINOIS.

DERRICK.

1,111,416.

Specification of Letters Patent. Patented Sept. 22, 1914.

Application filed August 27, 1913. Serial No. 786,987.

To all whom it may concern:

Be it known that I, JOHN L. TAYLOR, a citizen of the United States, residing at Chicago, in the county of Cook and State of Illinois, have invented certain new and useful Improvements in Derricks; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in derricks and comprises a simple and efficient apparatus of this nature having various details of construction and combinations and arrangements of parts which will be hereinafter fully described, shown in the accompanying drawings and then specifically defined in the appended claims.

I illustrate my invention in the accompanying drawings, in which:—

Figure 1 is a side elevation of a derrick made in accordance with my invention. Fig. 2 is an enlarged detail perspective view of a swiveled base to the swinging beam. Fig. 3 is a detail perspective view of a socket angle iron adapted to support the standard. Fig. 4 is a perspective view of a portion of the standard in which the member illustrated in Fig. 2 is adapted to be swiveled. Fig. 5 is a detail perspective of a seat for braces in the standard. Fig. 6 is an enlarged view in elevation of a portion of the standard, swinging beam and cable winding drum. Fig. 7 is a sectional view through the form shown in Fig. 6. Fig. 8 is a cross sectional view on line 8—8 of Fig. 1. Fig. 9 is a detail sectional view through a swivel connection. Fig. 10 is a view taken at right angles to the view shown in Fig. 6 and in section. Fig. 11 is a top plan view of the upper inclined side of the derrick beam. Fig. 12 is a plan view of the under inclined side of the derrick beam. Fig. 13 is an edge view of the part shown in Fig. 12. Fig. 14 is a detail perspective view of the base portion of the derrick, and Figs. 15, 16, 17 and 18 are sectional views taken respectively on lines 15, 15—16, 16—17, 17 and 18, 18 of Fig. 11.

Reference now being had to the details of

the drawings by numeral 1, 1 designate two channel base irons seated at angles to each other and to corresponding ends of said irons are fastened a casting 2, shown in Fig. 3 of the drawings, which is angular to fit over said irons and has two brace lugs 3 spaced apart and projecting from the upper surface thereof. An I-beam, designated by numeral 4, is adapted to engage the space intermediate said lugs 3, and rivets 5 are passed through registering apertures in said lugs and beam 4, thus forming a secure means for holding the standard upon the base portion. The casting 7, a detail of which is shown in Fig. 5 of the drawings, is adapted to be held by rivets 8 to the beams 1 and said castings 7 is provided with two beveled or inclined surfaces, designated by numeral 9, which surfaces are countersunk and are adapted to receive the lower angled end of an angled brace 10, which latter is held to the casting 7 by means of rivets 11 and, when thus fixed, the outer faces of said angle brace will be flush with the faces 12 of said casting 7. A socket member, designated by numeral 13, a detail of which is shown in Fig. 4 of the drawings, has two contracted flanged projections 14 at its lower end, which are spaced apart and provided with apertures 15, said projections 14 being spaced apart and adapted to fit over the upper end of the beam or standard 4, suitable rivets being passed through registering apertures in said projections 14 and the beam. The socket member 13 is provided with lugs 16 with double inclined faces 17 thereon and apertures 18 leading through the same, said inclined faces adapted to engage the upper angled end of the brace 10 which is fastened thereto by rivets 19 passing through registering apertures in the upper portion of the brace and the apertures 18. A swiveled beam carrying head 20 has a contracted shank portion 21 which is swiveled in said socket member, a shoulder 22 of said head being adapted to rest upon the upper end of the socket member 13.

Projecting from the outer circumference of the head 20 is a lug 23 having inclined faces 24 with apertures 25 therein. Said head has a flanged portion 26 and also an integral inclined projecting portion 27 with inclined faces 28 terminating at their lower ends in the shoulders 29. The derrick beam 110

is made up of three angle bars, designated respectively by numerals 30, 31 and 32, said bar 30 being adapted to be held by rivets 34 to the inclined surfaces 24 and their upper ends fastened together and secured to the pulley block 35. The bars 31 and 32 are held by means of rivets 36 to the inclined faces 28 and their upper ends are fastened to the pulley block 35.

10 Cast brackets, designated respectively by numerals 37 and 38, have three pairs of fingers, designated respectively by numerals 40, 41 and 42, a detail of one of said bars being clearly shown in Fig. 8 of the drawings, and which fingers 41 are adapted to engage the angle bar 30, while the fingers 40 engage the angle bar 32 and the fingers 42 the angle bar 31. Said angle bars are arranged with the intermediate angle bar 30 in an opposite direction from the angles of the bars 31 and 32 and, when held by the bracket members as shown, will tend to thoroughly brace one another and produce a beam which will withstand any strain which 20 might come upon it incident to raising heavy objects. Said brackets which tend to reinforce the angle bars will prevent any of the same from being bent and, when made as shown and described, will slip on the angle 25 portion of the bars and will be held securely in their clamping relation with the bars. This provides means for reinforcing the angle bars without the necessity of boring holes through the same which would tend to 30 weaken the bars.

Plates 40^x are bolted to the opposite sides of the head and are apertured for the reception of the reel shaft 41^x having handles 42^x fixed thereto and upon which shaft a winding 35 drum 43 is mounted. A suitable cable 44 is adapted to wind upon said drum and passes over a pulley 46 in the pulley block 35. The casting of said pulley block has a recess 47 formed therein, a detail of which is 40 shown in Fig. 9 of the drawings, and an opening through the bottom of said recess is adapted to receive the shank portion of the swiveled member 48, the upper end of which is flanged as at 49 and provided with a groove or raceway 50, co-operating with a raceway 51 formed in the bottom of said recess about the central opening therein for the reception of the ball bearings 52. A key 53 passes through the aperture in the 45 shank portion 48 of said member and serves to hold the balls in their proper raceways. An eye 54 in said member 48 is adapted to receive one end of the cable, as shown clearly in Fig. 1, and which cable passes about a pulley 56 mounted in the block 57 to which a hook 58 is connected. The upper ends of said plates 40^x are connected together by means of a bolt 59 passing through a tubular section 60 which holds the plates spaced 50 apart. A brake member 61 is pivoted at 62,

as shown in Fig. 10 of the drawings, affording means for frictionally engaging the cable to regulate the rotation of the drum.

When the angle bars 30, 31 and 32 are secured to the head and the different sized brackets 37 and 38 are secured thereto in the manner shown in Fig. 8 of the drawings, it will be noted that a derrick beam is produced of such a construction as will be thoroughly braced to allow the same to withstand an enormous weight incident to its use in hoisting heavy articles.

It will be noted that the two outside angle bars 31 and 32 are spaced apart and at their inner ends are wider than the length of the drum upon which the cable winds so that the cable traveling on the drum will not pass on the outside of either of the angle bars. This arrangement of the angle bars which form the beam will form a brace to prevent the load that is being hoisted on the cable collapsing sidewise. The intermediate angle bar 30 being longer than bars 31 and 32 and riveted to the swiveled head has its lower end adjacent to the top of the socket upon the standard, thus bracing against the load which is being hoisted by the cable.

What I claim to be new is:—

1. A derrick comprising a base and a standard fixed thereto, a socket member with a slot in its lower end arranged to receive the upper end of the standard, said base and socket member having lugs with inclined faces at angles to each other, an angle iron brace fastened to said inclined faces upon the lug and base, a head swiveled to said socket member, a drum mounted upon the head, angle irons fastened to said head and converging toward their upper ends, a pulley block fastened to said ends, a cable fastened at one end to said block and wound about said drum, a fall block pulley supported by the cable, a sheave in said block and over which the cable passes which is adapted to wind upon said drum, as set forth.

2. A derrick comprising a base and a standard fixed thereto, a socket member with a slot in its lower end arranged to receive the upper end of the standard, said base and socket member having lugs with inclined faces at angles to each other, an angle iron brace fastened to said inclined faces upon the lug and base, a head swiveled to said socket member, a drum mounted upon the head, said head having lugs upon its circumference with inclined faces at angles to each other, angle irons fastened to said inclined faces of the head and converging toward their upper ends, cast brackets with angled fingers engaging said converging angle irons, a pulley block to which the upper ends of the angle irons are fastened, a cable connected at one end to the block and wound about said drum, a fall block

pulley supported by the cable, and a sheave in said block over which the cable passes, as set forth.

3. A derrick comprising a base made up of channel bars fastened together at an angle to each other, a flanged casting fastened to the meeting ends of said bars which form the base, lugs projecting from said casting and spaced apart, a standard fastened between said lugs, a socket member with a slot in the lower end thereof to receive the top of said standard to which it is fastened, a head swiveled within said socket member, angle bars fastened at their lower ends to said head and converging toward their upper ends, bracket members connecting said converging bars, a drum mounted upon the head, a block fastened to the upper ends of said angle bars, a swiveled member mounted in said block, a cable fastened to said swiveled member, a fall block pulley about which the cable passes, and a pulley in said block over which the cable turns, said cable being wound about said drum, as set forth.

4. A derrick comprising a base made up of channel bars fastened together at an angle to each other, a flanged casting fas-

tened to the meeting ends of said bars which form the base, lugs projecting from said casting and spaced apart, a standard fastened between said lugs, a socket member with a slot in the lower end thereof to receive the top of said standard to which it is fastened, a head swiveled within said socket member, angle bars fastened at their lower ends to said head and converging toward their upper ends, bracket members connecting said converging bars, a drum mounted upon the head, a block fastened to the upper ends of said angle bars, a swiveled member mounted in said block, a cable fastened to said swiveled member, a fall block pulley about which the cable passes, and a pulley in said block over which the cable turns, said cable being wound about said drum, as set forth.

In testimony whereof I hereunto affix my signature in presence of two witnesses.

JOHN L. TAYLOR.
